UNITED STATES PATENT OFFICE.

CHARLES H. WATERMAN, OF PRIEST RIVER, IDAHO, ASSIGNOR OF ONE-HALF TO
DEAN A. GREGORY, OF PRIEST RIVER, IDAHO.

ANTISLIPPING DEVICE FOR BOOTS OR SHOES.

1,259,689.

Specification of Letters Patent. Patented Mar. 19, 1918.

Application filed April 15, 1916. Serial No. 91,378.

To all whom it may concern:

Be it known that I, CHARLES H. WATERMAN, a citizen of the United States, residing at Priest River, in the county of Bonner and

5 State of Idaho, have invented certain new and useful Improvements in Antislipping Devices for Boots or Shoes, of which the following is a specification, reference being had to the accompanying drawings.

10 This invention relates to an improved anti-slipping device for boots or shoes, and has for its primary object to provide improved means on the sole of heavy rubber boots or shoes such as are generally used by 15 lumbermen, which will effectually prevent slipping or sliding of the foot.

The invention has for another and more particular object to provide a device of the above character consisting of a plurality of 20 raised V-shaped rods or cleats molded upon the rubber sole of the shoe and a plurality of calks projecting from the face of each of said cleats.

25 It is a further object of my invention to provide a device of the above character which will be very effective in actual use, and may be embodied in the manufacture of the shoe at nominal cost.

With the above and other objects in view, 30 my invention consists in the novel features of construction, combination, and arrangement of parts to be hereinafter more fully described, claimed and illustrated in the accompanying drawing, in which,

35 Figure 1 is an inverted perspective view of a boot or a shoe provided with the present invention.

Fig. 2 is a longitudinal section.

40 Fig. 3 is an enlarged detail section showing the manner of attaching the calks; and

Figs. 4 and 5 are detail fragmentary perspective views illustrating two different forms of the ends of the cleats.

Referring in detail to the drawing, 5 45 designates the body of a rubber boot or shoe having a heavy sole 6, the surface of which is roughened or corrugated in the usual manner. Upon the bottom surface of this shoe sole, across the widest portion thereof, 50 the raised V-shaped ribs or cleats 7 are molded or integrally formed. The points or apexes 8 of these cleats are coincident with the longitudinal center of the shoe sole, and from the same, the arms or branches of the 55 cleats diverge rearwardly to the outer edges

of the sole. The cleats 8, at their ends, gradually decrease in thickness and merge into the outer rounded edges of the shoe sole. These cleats may be of the same material as the shoe sole and integrally formed 60 therewith or of a different material and suitably secured to the sole of the shoe.

In addition to the cleats 7, a relatively short transversely extending curved cleat 10 is formed upon the toe of the shoe sole. The 65 side face of each of the cleats is outwardly beveled or inclined, as at 11, to provide shelving surfaces which operate so as to prevent the collection and retention of snow between the cleats, said shelving surfaces of 70 the cleats causing the snow to readily slide off of the cleats.

The heel 12 of the shoe is also provided with a raised marginal cleat or rib 13, the inner side face of which is beveled or inclined, as at 14.

Each of the cleats or ribs is provided upon its bottom face with calks 15, said calks having elongated shanks 17 to extend through the cleats and the sole of the shoe, the extremities of said shanks being clenched upon the inner surface of the shoe sole. Upon each of the calk shanks, beneath the calk head, a washer plate 18 is engaged and preferably shrunk thereon. These washer plates 80 engage with the faces of the ribs or cleats 85 so as to effectually prevent the calks being forced through or embedded in the rubber cleats.

In Fig. 5 of the drawing, I have shown the 90 cleats as provided at their extremities with the relatively abrupt end faces which are beveled or inclined outwardly and merge into the body of the shoe sole, as shown at 19. It will be understood that any desired 95 number of the calks 16 may be employed upon each of the ribs or cleats. It is also manifest that, upon shoes to be used by men engaged in particular trades, a greater number 100 of the V-shaped ribs may be desirable.

From the foregoing description, taken in connection with the accompanying drawing, the construction and several advantages of my invention will be fully understood. By the provision of the raised ribs or calks 105 upon the shoe sole carrying the metal calks, slipping or sliding of the foot of the user upon treacherous surfaces, will be effectually prevented. The cleats may be readily formed or molded upon the rubber sole of the shoe 110

2
in its manufacture at but slight additional cost and the metal calks readily applied thereto.

While I have shown what I believe to be the preferred form and construction of the several features of my device, it will be understood that the same is susceptible of considerable modification therein, and I, therefore, reserve the privilege of resorting to all such legitimate changes as may be fairly embodied within the spirit and scope of the invention as claimed.

Having thus fully described my invention, what I desire to claim and secure by Letters Patent is:—

A rubber boot or shoe having a plurality

of spaced V-shaped cleats molded upon the sole thereof with their apexes pointing forwardly, the arms of the cleats diverging rearwardly and merging into the body of the shoe sole at the opposite edges thereof, the extremities of each of the cleats being beveled and the outer faces of the cleats being also beveled, the beveled portion of the cleats providing shelving surfaces.

25

In testimony whereof I hereunto affix my signature in the presence of two witnesses.

CHARLES H. WATERMAN.
